ATTY'S.

UNITED STATES PATENT OFFICE.

GEORGE P. MALLORY, OF YORKLYN, DELAWARE, ASSIGNOR, BY MESNE ASSIGNMENTS, TO SANITARY PRODUCTS CORPORATION OF AMERICA, OF PHILADELPHIA, PENNSYLVANIA, A CORPORATION OF VIRGINIA.

DWELLING PITMAN.

1,378,706.

Specification of Letters Patent.

Patented May 17, 1921.

Application filed August 30, 1919. Serial No. 320,809.

To all whom it may concern:

Be it known that I, GEORGE P. MALLORY, a citizen of the United States, residing at Yorklyn, county of New Castle, State of Delaware, have invented a certain new and useful Improvement in Dwelling Pitmen, of which the following is a specification, reference being had therein to the accompanying drawings.

10 The invention relates to a new and useful improvement in dwelling pitmen. It is applicable to any press of the crank shaft type. It is especially intended for application to a press having upper and lower 15 forming dies which are used for the forming and setting of articles made of sheet material, although it is applicable to any press of the crank shaft type in which a dwell is desired after the two members of 20 the press have come into contact with each other.

It has been found in practice that what is known to the die-maker as a dwell between the upper and lower forming dies comprising 25 a set is of great benefit in setting the piece to be formed, that is in case of material which has a tendency to spring away from the parts or dies over which they are formed. The momentary dwelling together 30 with the upper and lower dies will cause the piece which is being formed to adhere more truly to the lines of the die. This is especially true of paper and of fiber products. Heretofore a cam has usually been 35 employed to obtain this result but in a press in which this action is obtained by the use of a cam, the action is apt to be jerky and not smooth. One object of the present invention is to produce a dwelling pitman in 40 which the action will be smooth and free from jerky movement, and also reduce the number of parts as well as expense.

The invention will be fully understood from the following description when taken 45 in connection with the accompanying drawings, and the novel features thereof will be pointed out and clearly defined in the claim at the close of this specification.

In the drawings, Figure 1 is a front elevation partly in section of a machine embodying the invention, the two press members being shown as in their separated position.

Fig. 2 is a vertical section on line 2-2 of

Fig. 1, but showing the crank partially 55 rotated from the position shown in Fig. 1 sufficient to bring the upper die into contact with the lower die.

Fig. 3 is a section taken on the same line as Fig. 2, but showing the crank still further turned, being therein shown as at 180° from the position shown in Fig. 1.

Referring now to the drawings, 1 represents the base and 2 the upright portions of the frame. Within the uprights 2 there is 60 journaled a crank shaft 3 which may be operated in any suitable manner. Mounted on this shaft 3 are crank arms 4-4 carrying a crank pin 5. A pitman 6 is provided with a head 7 having a bearing through 65 which passes the crank pin 5. This bearing is a broken or split bearing having a movable seat portion 8 which is movable with relation to the pitman head 7 and a cap portion 9 which is rigidly secured to the 70 head portion 7 of the pitman. The movable portion 8 is mounted in a recess 10 in the pitman head so as to be slidable longitudinally with relation to the head and is seated upon a spring 11.

The pitman 6 is connected by a screw 12 with the ram 13 of the upper presser member by any suitable coupling, the connection shown being a ball and socket joint, comprising a ball 14 seated in a socket 15 in 85 the ram 13. Said screw 12 is adjustable with relation to the pitman 6 so that the elevation of the upper presser member may be varied with relation to the lower presser member.

Connected with the lower end of the ram 13 is a die 16 or any other suitable presser device. As shown in the drawings there is secured to the under side of the die 16 a cutting die 17 which is adapted to cut the 95 blank from a sheet of stock.

Mounted on a base support or bolster 18 is the lower presser member or die 19 which is stationary.

In operation the blank sheet is placed 100 across the top of the lower die 19, while the upper die is separated therefrom as shown in Fig. 1. When the shaft 3 has made a partial rotation so as to move the crank arms through a portion of the downward sweep, as shown in Fig. 2, the pitman will be caused to descend far enough to bring the upper presser member or die 17 into

pressing engagement with the blank which has been placed on top of the lower die, and if a cutter 20 such as shown in Fig. 2 is employed in connection with the upper die 17 it will also cut the blank for the article to be formed out of the blank sheet. At this stage of the movement the crank will have preferably moved through a trifle more than 90°, that is it will have moved a little more than half-way to the bottom of its downward stroke. During the continued movement of the crank to the bottom of its downward stroke, the crank pin 5 which rests upon the movable seat member 8 of the crank pin bearing will have pushed the said bearing downward upon the spring seat 11, as allowed by the recess 10 in which the bearing member 8 is inclosed, and will compress the spring 11 as shown in Fig. 3. This not only produces an elastic pressure of the upper presser or die member 17 upon the blank which is seated upon the lower presser member or die, but it also causes a dwelling of the upper presser member until in the continued rotation the crank and the crank pin 5 will have swung up on the return stroke to a point at the same elevation as that at which the upper presser member was first brought into contact with the blank on the lower die. Then the upper presser member will begin to rise during the remainder of the upward stroke of the crank.

The spring 11 should be a powerful spring, being strong enough to do the forming between the dies before the bearing member 8 begins to act to press the spring.

Having introduced the set of dies between the bolster 18 and the ram 13, and having set the ram by means of the adjusting screw 12, it is obvious that when the downward action of the ram is arrested by the upper and lower dies coming together that the bearing 8 will still continue to let the crank travel and the dies will dwell to-

gether until the gap between the bearing 45 and the slot in the head of the pitman is closed and will continue to so dwell until the bearing 8 has returned to its original position, and the ram of the press starts its upward movement. 50

The action of the dwelling pitman as described is applicable to any press of the crank shaft type when the pressure on the piece to be formed would not have to exceed the capacity of the spring that could be installed in the head of the pitman. The dwell can be regulated by the size of the gap between the bearing 8 and the head of the pitman; the larger the gap, the longer the dwell. 55

What I claim is:—

In combination with a crank shaft, a crank and a crank pin, a dwelling pitman carrying at its lower end a presser member, and having a head formed with a slot extending longitudinally in from the end thereof, and having an expansible bearing for the crank pin, said expansible bearing comprising two members separable from each other, each having a semi-cylindrical groove, the two grooves together forming a cylindrical bearing for the crank pin when the two semi-bearing members are closed together, one of said semi-bearing members being made fast to the end of the pitman and forming a cap for the said slot, the other of said semi-bearing members being slidable in said slot toward and away from said fixed semi-bearing member to expand the bearing, and a spring held in a socket in the 70 end of the pitman which forms a seat for said slidable member and causes the presser member to exert a yielding pressure, and which is compressible to allow a dwell of the pitman while the crank pin continues a 75 further downward movement. 80

In testimony whereof I affix my signature.

GEORGE P. MALLORY.
